MANIFOLD AIR INTAKE

Joseph N. Hull, Geneva-on-the-Lake, Ohio

Application December 16, 1931, Serial No. 581,474
Renewed March 9, 1934

8 Claims. (Cl. 123—124)

This invention relates to manifold air intakes for internal combustion engines.

An important object of the invention is to provide novel means for supplying additional air to a motor vehicle engine at a progressively increasing rate in accordance with the opening movement of the engine throttle.

A further object is to provide a device of the character referred to wherein the additional air is introduced in such a manner as to increase the turbulence in the fuel mixture passing into the motor to increase the explosive efficiency of the mixture.

A further object is to provide a novel device of the character referred to which is adapted to be readily and easily connected to the intake of the vehicle engine.

A further object is to provide means automatically operative for preventing the supply of additional air upon operation of the carburetor choke valve while the motor is being started.

Other objects and advantages of the invention will become apparent during the course of the following description.

In the drawing I have shown one embodiment of the invention. In this showing,

Figure 1 is a side elevation of a portion of the vehicle engine showing the invention applied,

Figure 2 is an enlarged fragmentary side elevation of the device showing it in position on a portion of the intake manifold.

Figure 3 is an enlarged detail section taken substantially on line 3—3 of Figure 2, and

Figure 4 is a transverse section on line 4—4 of Figure 2.

Referring to Figure 1 the numeral 10 designates a motor vehicle engine having the usual exhaust manifold 11 and intake manifold 12, the latter being provided with a vertical portion 13 connected at its lower end to a carburetor 14. The carburetor is provided with a throttle 15 connected to a rock shaft 16 operable by one end of a bell crank lever 17. A throttle control rod 18 is connected to the bell crank lever 17. The carburetor is further provided with the usual air intake 19 in which is arranged a choke valve 20 operable by an arm 21. The elements described are conventional in construction and form no part of the present invention.

The device forming the subject matter of the present invention comprises a cast cylindrical body indicated as a whole by the numeral 22 and formed in complementary sections 23 and 24. The body of the device is adapted to be arranged

around the vertical pipe 13 and to be secured in position by suitable fastening elements such as screws 25.

The body section 23 is axially enlarged as at 26, and this enlarged portion carries oppositely extending preferably angularly arranged extensions 27 grooved as at 28 to form a guide of dovetail cross-sectional shape.

The guide 28 is provided throughout its length with a substantially flat preferably machined inner face 29. The body section 23 is longitudinally slotted as at 30 to provide an air intake port which communicates with a preferably circular opening or port 31 formed in the pipe 13. While the portion of the port 30 extending through the face 29 of the guide is in the form of a longitudinal slot 70 having parallel sides, the port 30 is altered in shape inwardly so that its inner extremity coincides in shape and size to and registers with the opening 31.

A pair of slide valves 32 and 33 are operable in the guide 28. With the throttle in idling position, the adjacent edges of the valves 32 and 33 contact with each other substantially at the position indicated in Figure 3. The upper end of a rod 34 is pivotally connected as at 35 to the upper end of the valve 32. The lower end of the rod 34 is pivotally connected as at 36 to the other arm of the bell crank lever 17. A second operating rod 37 has its upper end pivotally connected as at 38 to the lower end of the valve 33, and the lower end of the rod 37 is pivotally connected as at 39 to the arm 21.

The operation of the device is as follows:

The vertical pipe 13 is drilled radially to provide the opening 31 of the proper size whereupon the body sections 23 and 24 are clamped about the pipe 13 with the inner extremity of the port 30 registering with the port 31. The rods 34 and 37 are then connected respectively to the bell crank lever 17 and arm 21.

In operation, the choke valve 20 is not normally operated, while the throttle 15 is almost constantly changing position, as is well known. When a pull is exerted on the throttle rod 18, the bell crank lever 17 is swung in a counter-clockwise direction to open the throttle, and the movement of the bell crank lever is transmitted through the rod 34 to the valve 32 to progressively move the latter upwardly in accordance with opening movement of the throttle. Since, under normal conditions, the valve 33 remains stationary, the upward movement of the valve 32 progressively uncovers the port 30 to admit air through the port 31 into the vertical pipe 13. It will be apparent that the outer extremity of the 110

port 30 will be uncovered to a greater extent to increase the rate of flow of air into the manifold as the throttle is opened to increasing extents. However, regardless of the degree of opening of 5 the port 31, the additional air will always be supplied to the intake manifold at the same point through the same sized opening 31 with the air always moving in the same direction. It has been found that the introduction of the air through a 10 circular relatively small opening creates a condition of great turbulence in the fuel which results in greatly increased mileage from the fuel without an attending loss of power.

When it is desired to start the vehicle and to 15 use the choke in accordance with standard practice, the operator merely pulls out the choke button on the dash and operates the starter in the usual way. The operation of the choke causes the arm 21 to swing in a clockwise direction, thus 20 moving the arm 37 and valve 33 upwardly. The valve 33 thus operates as a follower for the valve 32 to prevent the port 30 from being opened to the atmosphere, which would be undesirable when starting the vehicle. The valve 33 under such 25 conditions serves the additional function of moving the valve 32 upwardly, and this movement is transmitted to the throttle through the rod 34 and the lever 17, and thus the throttle is automatically opened upon operation of the choke 30 valve as is desirable. The device accordingly facilitates the operation of starting the motor vehicle engine.

It will be apparent that the device may be 35 cheaply manufactured because of its simplicity in construction, and that it readily may be applied to the manifold. In practice it has been found that there is no noticeable loss in power in the use of the device, but that great fuel economy is effected.

40 It is to be understood that the form of the invention herewith shown and described is to be taken as a preferred example of the same and that various changes in the shape, size and arrangement of parts may be resorted to without departing from the spirit of the invention or the 45 scope of the subjoined claims.

I claim:

1. An attachment for an intake manifold supply pipe having a radial opening therein, comprising a body adapted to be arranged against the manifold pipe and having a port corresponding in shape and size to and adapted to register with said opening, said body having an outer face through which said port extends, and a valve movable to progressively open and close said port and slideable across the outer face of said body, the outer end of said port being elongated in the direction of movement of said valve.

2. An attachment for an intake manifold supply pipe having a radial opening therein, comprising a body formed of complementary sections adapted to be arranged against the manifold pipe, one of said sections having a port the inner end of which corresponds in shape and size to and is adapted to register with said opening, said last named section having an elongated outer face through which the outer end of said port extends, said port having its outer end formed relatively long and narrow and arranged parallel to the direction of elongation of said outer face, and a slide valve movable against said face longitudinally with respect to the outer end of said port to progressively open and close the latter.

3. An attachment for an intake manifold supply pipe having a circular radial opening there-

in, comprising a body adapted to be arranged against the manifold pipe and having a port the inner end of which corresponds in shape and size to and is adapted to register with said opening, said body having an outer face through which said port extends, and a valve movable to progressively open and close said port and slideable across the outer face of said body, the outer end of said port being elongated in the direction of movement of said valve, and a follow up valve for said first named valve movable therewith to prevent the opening of said port when said first named valve is operated.

4. An attachment for an intake manifold supply pipe having a circular radial opening therein, comprising a body formed of complementary sections adapted to be arranged against the manifold pipe, one of said sections having a port the inner end of which corresponds in shape and size to and is adapted to register with said opening, said last named section having an elongated outer face through which the outer end of said port extends, said port having its outer end formed relatively long and narrow and arranged parallel to the direction of elongation of said outer face, a slide valve movable against said face longitudinally with respect to the outer end of said port to progressively open and close the latter, and a follow up valve movable with and against said first named valve to prevent the opening of the outer end of said port upon movement of said first named valve.

5. An attachment for an intake manifold supply pipe having a circular radial opening therein, comprising a body adapted to be arranged against the manifold pipe and having a port corresponding in shape and size at its inner end to said opening and adapted to register therewith, said body having an outer face through which said port extends, a valve progressively movable to open and close said port and slideable across the outer face of said body, the outer end of said port being relatively narrow and elongated in the direction of movement of said valve, means for connecting said valve to the throttle of the engine to be progressively opened therewith, and an auxiliary valve movable with said first named valve to prevent the opening of said port.

6. An attachment for an intake manifold supply pipe having a circular radial opening therein, comprising a body adapted to be arranged against the manifold pipe and having a port corresponding in shape and size at its inner end to said opening and adapted to register therewith, said body having an outer face through which said port extends, a valve progressively movable to open and close said port and slideable across the outer face of said body, the outer end of said port being relatively narrow and elongated in the direction of movement of said valve, means for connecting said valve to the throttle of the engine to be progressively opened therewith, an auxiliary valve arranged in end to end relation with said first named valve and movable therewith to prevent the opening of said port, and operating connections between said auxiliary valve and the choke valve of the carburetor connected to the manifold.

7. An attachment for an intake manifold supply pipe having a circular radial opening therein, and a carburetor connected to the manifold, comprising a body adapted to be arranged against the manifold pipe, said body having a port the inner end of which corresponds in shape and size to and is adapted to register with said open-

ing, said body having an elongated outer face through which the outer end of said port extends, said port having its outer end formed relatively long and narrow and arranged parallel to the direction of elongation of said outer face, a valve mounted against said outer face for linear sliding movement longitudinally thereof to progressively open and close said port, operating connections between said valve and the throttle valve of the carbureter for effecting simultaneous opening movement of said valves, an auxiliary valve arranged against said outer face in end to end relation with said first named valve and slidable therewith to prevent the opening of said port, and connections between said auxiliary valve and the choke valve of the carbureter to effect simultaneous movement thereof.

8. A device constructed in accordance with claim 7 wherein said body is provided with a portion elongated on opposite sides of said port and provided with a single open ended guide of dovetail cross-sectional shape in opposite end portions of which said first named valve and said auxiliary valve are slidable.
